UNITED STATES PATENT OFFICE.

TELFORD CLARENCE BATCHELOR, OF WEST KENSINGTON, COUNTY OF MIDDLESEX, AND ARTHUR LATCH, OF SOUTH SHIELDS, COUNTY OF DURHAM, ENGLAND.

WIRE CABLE.

SPECIFICATION forming part of Letters Patent No. 403,319, dated May 14, 1889.

Application filed March 6, 1888. Serial No. 266,317. (Specimens.) Patented in England August 25, 1888, No. 12,285.

To all whom it may concern:

Be it known that we, TELFORD CLARENCE BATCHELOR and ARTHUR LATCH, subjects of the Queen of Great Britain, residing, respectively, at 8 Barons Court Road, West Kensington, county of Middlesex, England, and at Biddick Hall, South Shields, county of Durham, England, have invented new and useful Improvements in Wire Cables, (for which we have obtained Letters Patent in Great Britain, No. 12,285, of August 25, 1888,) of which the following is a specification.

Heretofore wire cables have been composed of strands each comprising several wires 15 twisted together, such strands also being spirally wound or twisted together to form the rope or cable. In the prior constructions the completed cables are composed of strands round or circular in cross-section, and consequently their outer surfaces present very few individual wires to the surface of wheels or rollers at the point of contact, so that the cable runs in a very marked manner upon the particular individual wire presented to the 20 pulley as a point of support, which causes excessive strain and wear to be placed upon that particular wire, in addition to which the wire bears the crushing action due to the weight of the cable while passing over a wheel or 25 roller. In some instances a cable made of strands, as above set forth, has been enveloped by wires laid thereupon and conforming to the round or circular shape in cross-section, but in case of fracture of such external wires 30 they would unravel and the rope be rendered useless.

The object of our invention is to avoid the above objections, to improve the construction of wire cables, and to provide a wire cable 40 built up of a series of substantially flattened strands each comprising several wires and a core, so that a plurality of wires must at all times bear uniformly on a wheel or roller continuously throughout the length of the cable. 45 The objects of our invention we accomplish by the novel features of construction and arrangement of parts hereinafter described and claimed, reference being made to the accompanying drawings, in which—

Figure 1 is a transverse sectional view of a 50 wire cable embodying our invention; Fig. 2, a side elevation of a portion of the same; Fig. 3, a transverse sectional view of a cable, showing a modification; Fig. 4, a side elevation of a part of one of the strands composing 55 the cable shown in Figs. 1 and 2; Fig. 5, a transverse sectional view of the strand shown in Fig. 4; Fig. 6, a transverse sectional view of one of the strands composing the cable shown in Fig. 3, and Fig. 7 a sectional plan 60 view of a modified construction of strand.

In order to enable those skilled in the art to make and use our invention, we will now describe the same in detail, referring first to Figs. 1 and 2, where it will be seen that the 65 cable is composed of a central core, D, of suitable material, preferably hemp or other flexible substance, about which are spirally wound six strands, each strand being substantially flattened and composed of two cores, A B, Figs. 70 4 and 5, about which are spirally wound the external wires, C. The cores A B are each made up of a series of wires spirally wound together, like an ordinary wire rope, and when two of such cores are laid parallel to each 75 other, Fig. 4, and the external wires, C, are laid spirally thereupon, the strand so produced will be substantially flattened, the opposite surfaces each comprising a plurality of wires. A series of these strands—say six—80 being spirally wound on a core, D, a cable is produced, such as shown in Figs. 1 and 2.

In the construction shown in Fig. 3 each strand, instead of having opposite and parallel substantially-flattened sides, as in Fig. 5, 85 is substantially triangular in cross-section, and comprises three cores, A A B, each core being made of a series of spirally-wound wires in the same manner as described with reference to Fig. 4. The three cores being laid 90 together, as in Fig. 6, and the external wires, C, wound spirally thereupon, it follows that the completed strand will be provided with three substantially-flattened sides, each comprising a plurality of wires.

A cable may be made to embody our invention from strands—such as shown in Fig. 7—95 where the cores A B are each composed of a sin-

gle wire, on which the external wires, C, are spirally wound, so as to provide opposite and parallel substantially-flattened sides or surfaces.

5 By our construction of a cable it is impossible for a single wire alone or any two wires alone to come solely in bearing-contact with a wheel or roller; but, on the contrary, a plurality of wires of each strand will bear on the 10 wheel or roller, and consequently this greatly increases the durability of wire cables.

In a cable made up of substantially-flattened strands, as described and shown, a plurality of wires comes at all times during the 15 traveling movement of the cable in contact with the wheel or roller or other support, so that we avoid running the cable on a particular wire, which is objectionable, as before stated.

20 The series of substantially-flattened strands when made into a cable are so arranged that they conjointly conform to the exterior surface of the cable approximating to a circle, and as the external wires of each strand are 25 spirally wound around its wire core said external wires are carried to the inside of the cable at frequent intervals, so that in the event of fracture of any one or more of the wires the unraveling would only occur for the 30 distance such wire or wires are exposed on

the outer surface, which part could be cut out without destroying the usefulness of the cable.

What we claim is—

1. A wire cable composed of a series of spirally-wound substantially-flattened strands, each strand comprising a core and spiral wires thereupon, substantially as described. 35

2. A wire cable composed of a central core and a series of spirally-wound substantially- 40 flattened strands thereupon, each strand comprising a wire core and spiral wires thereupon, substantially as described.

3. A wire cable composed of a central core and a series of spirally-wound substantially- 45 flattened strands thereupon, each strand comprising independent cores A, B placed side by side, and spiral wires C thereupon, substantially as described.

In witness whereof we have hereunto set our 50 hands, in the presence of two subscribing witnesses, this 1st day of February, 1888.

TELFORD CLARENCE BATCHELOR,
ARTHUR LATCH.
